METHOD FOR MAKING BATHING CAPS AND ANALOGOUS ARTICLES

Original Filed May 7, 1927

UNITED STATES PATENT OFFICE

JACOB STEIN, OF NEW YORK, N. Y.

METHOD FOR MAKING BATHING CAPS AND ANALOGOUS ARTICLES

Original application filed May 7, 1927, Serial No. 189,725. Divided and this application filed January 7, 1928. Serial No. 245,227.

The present invention is a method for the production of so-called "bathing" caps, which are generally made up of impervious sheet material, such as rubber, and used for maintaining the hair or head dry while bathing, but the present invention relates more particularly to the production of so-called "shower caps", that is, of the skull-fitting type, usually having an ornamental border of 10 different colored material and which serves as a head band and reinforcement of the head opening. However, it is to be understood that other types of caps within reasonable limits may be produced by the present invention with or without the different colored border.

It is well known that various methods have been proposed for the making of such caps, but they require numerous manual operations which are expensive, slow and unsatisfactory from the standpoint of accuracy and quantity production.

The present invention is an improved method aiming to overcome the above stated 25 drawbacks and the production of articles of the above stated character more economically and in greater numbers than heretofore for a given number of operations or in a given time.

30 A further object of the present invention is an improved method by which two or more caps or articles may be made from a width of opposed sheets of material.

The invention includes the novel process 35 hereinafter described and particularly defined by the appended claims.

In order that the manner of carrying out the process may be better understood, drawings are appended hereto, in which:-

40 Figure 1 is a perspective view showing the initiate steps or manner of handling or arranging the materials which enter into the construction of cap or article in accordance with the method of this invention, mainly 45 folding of a border or band strip and arranging it in relation with the body strip C or D and then severing or slitting said body and band strips.

50 Figures 2 and 2a show body sheets and band strips from which complemental por-

tions of the article produced according to this invention are provided and further illustrates the relation or position of the band strips relative to the body sheet before slitting or severances.

55 Figures 3 and 3a are diagrammatic views showing the materials being operated upon by a suitable splitting or cutting device;

Figures 4 and 4a are views showing the 60 severed edges of the material spaced to permit the unfolding of the band-strips f without over-lapping;

Figures 5 and 5a show the band-strips unfolded;

Figure 6 shows the corresponding severed 65 sheet sections of the cap material C and D, shown in Figures 2, 3, 4 and 5, brought face to face or in superposed relation and the manner of cutting the assembled sheet sections to produce the complete articles; 70

Figure 7 is a plan view of the assembled sheets in Fig. 6, the dotted line 40 indicating the line of severance or cutting to produce the article or cap; and

Figure 8 is a view of a completed cap. 75

The method employed to accomplish the above stated purposes broadly resides in providing two sheets of substantially equal width C and D, Figure 2, or two sources of supply of said sheet material, which form the body 80 of the cap. These sheets are brought face to face or to opposed relation (see Fig. 6) and then subjected to the action of a suitable cutting tool or device 14 to sever and obtain from the sheets the article desired (see Figs. 7 85 and 8). When the sheet materials are unvulcanized rubber, the severed edges of the opposed sheet portions of the article are joined to each other by means of this cutting action as is commonly understood in the art and, in 90 the manufacture of articles such as bathing caps or the like, the head opening of the cap is formed by the edge of the sheet material which is not subjected to the cutting operation, (see Figure 8).

95 More specifically, the method includes the intermediate steps of placing or applying narrowed band strips F, longitudinally, one to each of said body sheets, respectively, along a medial line thereof (see Figures 1 and 2); 100

then subjecting the sheets to the cutting action of a tool or device 13 along a medial line of said band strips F for severing the band and body in two and securing the adjacent edges h of said band and body material together, when the materials are of unvulcanized rubber (see Fig. 3). The next step of the method consists in spacing apart said severed edges of the sheet material C and D, 10 and unfolding the split or severed portions f of strips F to form an extension of the cap body sheet, as illustrated in Figures 4 and 5.

It is, of course, understood that the two cap body sheets C and D are treated in the manner above stated, the severed or divided portions 2 and 3 of sheet C being brought face to face or in opposed relation with the like portions 4 and 5, respectively, of the other sheet D to provide cap or article forming strips, as shown in Figures 6 and 7. These cap strips are then each subjected to a cutting operation, preferably of a die cutter 14, for removing from each article or cap strip a semi-oval shaped portion forming the cap (see Figures 6 and 7). Of course, it is understood that the shape of the line of severance 9 may vary according to the article produced. This cutting operation, when severing unvulcanized sheet rubber, unites the adjacent severed edges i of the opposed sheet portions forming the cap and intersects the edge of the border or band strips f, which edges form the head opening of the cap 10. Otherwise, it is necessary to cement, stitch or 35 suitably secure together the edges to be united. Rubber articles, thus provided, are then suitably vulcanized.

It is desirable in many instances to have the border strips or bands f of double or reinforced strength, and, therefore, the strips F (shown in Figures 1 and 2) are folded, as at 15, upon themselves at their marginal edge portions before the materials are subjected to the action of the cutting tool 13, illustrated in Figure 3, which, after this splitting, form the bands f of double thickness.

In accordance with the present disclosure the sheets of material C and D are of a width at least that of the double depth of the cap 40 to be made and are divided longitudinally in the separate sections, one section from each of the sheets C and D being brought in opposed relation to form the article, thus enabling production of two caps simultaneously 45 from a width of opposed sheets of material. In order that the section 2-4 and 3-5 may be held from slipping out of position during the handling or the operation of the tool 14, these are secured together, as at 16 and 17, 50 by stitching, pinching or the like.

The operations or steps above described may be done continuously or in immediate succession, the sheets C and D and the strips F being fed from any suitable source to or 55 between folders, cutters, spacing devices, un-

folders and conveyor means which bring the treated sheet sections 2, 3, 4 and 5 in opposing relation, shown in Figure 6, or the steps may be carried out by merely manual operations.

It is, of course, understood that while the method of this invention has been described specifically in connection with the manufacture of bathing caps, it is not limited thereto because it may be obviously applied and used in the manufacture of other analogous articles. 70

This application is a divisional application of the copending application for Letters Patent, Serial No. 189,725, which matured into Patent No. 1,746,845. 80

Having thus described the invention and in what manner the same is to be performed, that which is claimed as new is:

1. A method of making bathing caps and analogous articles including applying a relatively narrow strip of material along a medial line on a surface of each of two sheets of rubber and cutting each strip and sheet to divide the same into two parts and unite the severed edges of the strip and sheet, then bringing the severed sections of one sheet in opposed relation with corresponding sections of the other sheet, then cutting the opposed sections along a line intersecting the free edge of said attached strip at two points thereof, and uniting said last mentioned severed edges. 90

2. A method of making bathing caps and analogous articles including applying relatively narrow strip of rubber along a medial line on a surface of each of two sheets of rubber and cutting each strip and sheet to divide the same into two parts and unite the severed edges of the strip and sheet, thus providing two sheet sections from each sheet with a folded marginal portion, then unfolding said marginal portions and bringing the severed sections of one sheet in opposed relation with corresponding sections of the other sheet, then subjecting the opposed sections to a cutting operation along a line intersecting the free edge of said attached strip at two points thereof and which also joins the severed edges. 100

In testimony whereof I have hereunto set my hand. 105

JACOB STEIN.
